UNITED STATES PATENT OFFICE.

CHARLES ELMER POPE, OF HOLYOKE, MASSACHUSETTS, ASSIGNOR TO GREAT NORTHERN PAPER COMPANY, OF MILLINOCKET, MAINE, A CORPORATION.

WINDING-REEL FOR PAPER.

1,248,542.

Specification of Letters Patent.

Patented Dec. 4, 1917.

Application filed July 13, 1915. Serial No. 39,696.

To all whom it may concern:

Be it known that I, CHARLES E. POPE, a citizen of the United States, residing at Holyoke, in the county of Hampden and State of Massachusetts, have invented an Improvement in Winding-Reels for Paper, of which the following is a specification.

This invention relates to means for winding the web of paper produced by a paper-making machine onto a winding-roll. Ordinarily two or more winding-rolls are employed, and the web is wound first on one roll and then on another. When one roll has become filled, the web is severed and the newly-formed end-portion is carried over by hand onto another roll. On slow moving machines this means operates satisfactorily, but on high-speed machines, which run at say 1,000 ft. per minute, it is impossible to sever the web and carry the newly-formed end-portion by hand onto another roll quickly enough to avoid a large amount of waste, or the stopping of the machine.

This invention has for its object the provision of means for starting the winding of newly-formed end-portion of the web on an empty winding-roll while the web is being severed usually in a slanting direction, and while the other end-portion, formed by severing the web, is being wound on a substantially filled winding-roll, so that the winding operation may be continued without interruption and the usual hand method of carrying-over avoided.

In carrying out this feature of my invention a winding-roll is supported in a position herein termed its waiting position, in such manner as to admit of a bodily movement into cooperative relation with an under-roll, over which the web of paper is passing at the moment the web is severed, this second position being termed its starting position. The newly-formed end-portion of the web begins to wind on said roll and as soon as the web has become firmly fixed to said roll by the winding action, the roll is moved into another position with respect to said under-roll, this position being termed its running position, where it remains until the roll has become filled, such movement into running position enabling an empty winding-roll to be brought into waiting position, preparatory to being

moved into starting position, when required, hence provision is made for two winding-rolls.

As soon as the roll which is in running position has become filled, the web is severed, usually in a slanting direction, the empty roll having previously been moved into starting position to receive the newly formed end-portion, and while the web is being wound on said roll in its starting position, the filled roll is removed to enable the next roll to be moved from its starting position to its running position, thus providing for a continuous winding operation of the web.

To support the winding-rolls in their starting and running positions, two separate supporting frames are provided, which are movable with respect to each other, which frames are also constructed and arranged to admit of transference of a roll from one to the other frame, from its starting to running position, and herein said frames are termed, respectively, the starting and running frames.

In view of the fact that the web occasionally breaks at some part of the machine, means are herein provided to deflect a newly formed end-portion of the web onto and along suitable guiding-means by which it is delivered to the winding-means, said deflecting means preferably including a forcibly delivered jet or sheet of air or steam. To avoid the necessity of deflecting the newly-formed end-portion at the exact moment it arrives in front of the forcibly delivered jet or sheet of air, a chute is provided down which said end-portion passes, and a cutter-bar is associated with said chute, and the deflecting-means is arranged at the top of the chute to deliver the jet or sheet of air against the web, to deflect it and cause it to engage the cutter-bar by which it is severed and a newly formed end-portion produced, and simultaneously deflected onto and along the guiding-means.

Figure 1 is a side elevation of a portion of a papermaking machine having winding-means for the paper, embodying my invention.

Fig. 2 is a plan view of the same.

Figs. 3, 4 and 5 are transverse sectional details of the winding-means in different positions.

Fig. 6 is a detail of one of the carriers for the winding-roll to be referred to.

Fig. 7 is a detail illustrating the act of severing of the web of paper.

5 Fig. 8 is a modification of my invention wherein the web is taken from a calender instead of from the machine itself.

Referring to the drawings, Figs. 1 to 7, 10 represents a drying-roll or press-roll of an ordinary papermaking machine, which may be the last drying-roll or press-roll of a Fourdrinier machine; 12 a belt associated therewith; 13 a blade pivoted at 14, and held in engagement with said roll 10 by a weight 15, said blade serving to direct the web of paper 16 downward into a chute 17, under certain conditions of the operation of the machine. 18 is a stationarily supported cylindrical or other-shaped bar extended transversely from side to side of the machine and arranged between the roll 10 and the chute 17, in front of the blade 14. The web engages and is drawn forward beneath said bar in its progress to the winding-means and passes through the space between said bar and blade when passing to the chute. Another stationarily supported cylindrical bar 20, like the bar 18, is arranged in front of and in parallel relation with said bar 18, 20 and preferably at a lower elevation. A series of bars 21 are attached at their ends to the bars 18 and 20, respectively, said bars 21 being extended longitudinally of the machine and arranged in parallel relation with 30 narrow spaces between them. As the bar 20 is arranged below the plane of the bar 18, said bars 21 are inclined in a downward direction. Said bars and their end-supports form a grid and serve to guide the web to 35 the winding-means; and also more particularly as a means to support an end-portion of the web and direct it onward when a free end-portion is blown or otherwise projected against them.

40 45 This guide is disposed in a plane above the top of the chute, so that in case the web is passing downward into the chute, it may be deflected, in a direction toward said guide, as represented by dotted line, Fig. 1, and 50 held in engagement therewith and moved along thereon to the winding-means.

As a means to deflect the web at the top of the chute, I may employ air-forcing or steam-forcing means of any suitable kind 55 by which numerous jets of air or steam or a sheet of air or steam, or its equivalent, may be projected against the web, and, as here shown, a pipe 25, which may be connected with any suitable forcing-device, is 60 arranged at the side of the machine, having a horizontal pipe 26 extended transversely of the machine at or above the top of the chute, said pipe having a plurality of perforations or one or more slits, for the issuance of air or steam, which passes over and

across the top of the chute, beneath the blade 14, and forcibly engages the web and deflects it in a direction toward the guide.

Arranged in the upper part of the chute is a stationarily supported cutter-bar 28, 70 over which the web is drawn when thus deflected, and by pressure against the toothed edge of said bar it is severed, thus to form a free end-portion which is blown against the guide and moved along thereon. This 75 means of severing the web to form a new end-portion and to convey it to the winding-means is provided purposely in case of a break happening to the web at some part of the machine, and as such happenings are 80 of frequent occurrence, provision of some means becomes necessary, particularly in high-speed machines. It will be observed that this means is automatic in action and does not require any great amount of skill 85 on the part of the operator, it only being necessary to turn on the air, although it is obvious that the air may be turned on all the time, if desired.

The winding-means for the web will now 90 be described. 30 represents a large cylindrical roll extended transversely of the machine, and arranged in front of the bar 20 of the guiding-means to receive the web therefrom, and serves as the under-roll. 95 Two rolls are employed upon which the web is to be wound, which are represented at 31 and 32, and said rolls are designed to be successively brought into coöperative relation with said under-roll 30. The rolls 31 and 32 100 each have journals 34 arranged in boxes 33, the journals extending through the boxes and projecting therefrom a short distance. These boxes are held against longitudinal movement on the journals. In addition to 105 these rolls, any number of spare rolls, similarly constructed, may be employed.

Two separate supporting frames are provided for the winding-rolls, one arranged to receive the boxes and hold a winding-roll 110 in starting position, and the other arranged to receive the journals and hold a winding-roll in running position. Said frames are so constructed and arranged relative to each other that the winding-roll which is arranged in the starting-frame and held by it in starting position may be automatically transferred to the running-frame, after which the starting-frame may be returned by hand and an empty-roll placed therein, 120 in readiness to be moved into engagement with the under-roll 30.

The starting-frame for holding a winding-roll in starting position, as here shown, consists of a pair of like sectors 40, arranged 125 at opposite sides of the machine and pivoted at 41 to side-frames 42 of the main frame-work, said pivots being eccentric to the axis of the under-roll 30, and arranged above said axis. Said sectors have 130

toothed edges 43, concentric to their pivots 41, arranged for engagement with pinions 44, on a shaft 45, extended transversely in the machine, and bearing a hand-wheel 46, by which it may be turned. Said sectors have recesses at 47, to slidably receive the boxes 33. Turning of the shaft 45 in a direction toward the left, operates to move the sectors on their pivots, and thereby move the 10 winding-roll supported by them into a waiting-position, see Fig. 1, where it is free from contact with the roll 30, and then into starting position, see Fig. 3, wherein it engages the roll or the web thereon; and turning of 15 the shaft in a direction toward the right, operates to move the winding-roll into running position, see Figs. 4 and 5.

The running-frame consists of a pair of upright arms 50, secured to a transverse shaft 20 51, extended from side to side of the machine and having a hand-wheel 52 for turning it. The extremities of said arms have open boxes 53, adapted to receive the journals of a winding-roll. Turning of the 25 shaft in a direction toward the right, operates to move said arms into a position to receive a winding-roll, see Fig. 3, and said arms are moved in the opposite direction by the accumulating paper on the roll, see Figs. 30 5 and 6.

In beginning the winding operation an empty winding-roll 31, will be moved into coöperative engagement with the under-roll, and the free end-portion of the web 35 from the delivering means will be passed into the bite of said rolls. Said free end-portion may be deflected against the guiding-means by a blast, and thus guided into the bite of said rolls, or it may be otherwise 40 brought into such position. In any event the rolls will engage the free end-portion and draw it along, and when said free end-portion emerges from the other side of the rolls, it will be deflected or reversed by a 45 blast or other means, back onto the surface of the empty winding roll, and preferably held thereon while said roll rotates a few turns. As soon as the web has been wound several turns on the winding-roll so as to 50 become firmly fastened thereto, said starting-frame is moved counter-clockwise to bring the journals of said winding-roll into the recesses 53 at the ends of the arms 50 of the running-frame, as represented in Fig. 4, 55 the boxes 33 being caused to slide outward and the winding roll being moved bodily through a short arc. The web continues to be wound on said winding-roll, and as it accumulates thereon and the roll increases in 60 diameter, the boxes bearing said roll are caused to slide farther outward, and such sliding movement continues until the boxes leave their recesses. The journals of said roll are then supported solely in the recesses 65 at the extremities of the arms of the run-

ning-frame, as represented in Fig. 5. The paper then continues to be wound on said roll until the roll is filled or thereabout.

While the paper is being wound on the winding-roll with said roll in running position, the starting-frame is returned to its waiting position, and an empty winding-roll is placed therein, preparatory to being moved into starting position. When the roll on which the paper is being wound becomes filled, an empty roll, which is at such time supported by the starting-frame in waiting position, see Fig. 1, will be moved into starting position, into engagement with the moving web on the under roll, and will 70 be rotated thereby, and temporarily the moving web will pass beneath the rotating empty roll while it is being wound upon the other roll. With the two winding rolls in 75 these positions, the web is severed, at a place between them, by any suitable means, such as a nozzle 60, arranged to forcibly deliver a jet of air, steam, or water beneath the web on the under roll, at a point between said rolls, see Fig. 7, the line of severance being 80 in a slanting direction owing to the movement of the web. While the web is being thus severed, the newly-formed end-portion is deflected by the jet onto the empty roll, and is wound upon said roll, and the 85 other end-portion is wound upon the filled roll. By this construction and arrangement, the operation is continuous. Then the filled roll will be removed from the running-frame by any suitable means, such as a block and 90 tackle, and said running-frame will be returned to the position shown in Fig. 3, preparatory to a repetition of the operation.

To limit the movement of the running-frame it may have an arm 65, secured to its 105 shaft which extends downward, and the lower end-portion of said arm arranged for movement between limiting-stops 66, 67.

In lieu of taking the web of paper from a paper-making machine it may be taken 110 from a calender, as represented in Fig. 8, wherein 70 represents the lower roll of a calender.

It will be observed that the winding-means is essentially automatic, and is especially adapted for high-speed machines wherein it is very difficult to sever the web, and cause a newly-formed end-portion to engage another winding-roll quickly enough to prevent interruptions of the travel of the 120 web.

I claim:—

1. The combination of delivering-means for a web of paper, winding-means therefor including an under-roll over which the web 12 passes, two winding-rolls, means to support both of said winding-rolls in coöperative relation with said under-roll which admits of their separate coöperative relation therewith, the web being severed between the 130

winding rolls while both said rolls are in co-operative relation with the under roll.

2. The combination of delivering-means for a web of paper, winding-means therefor including an under-roll over which the web passes, two winding-rolls, means arranged to support said winding-rolls in co-operative relation with said under-roll, respectively, in starting and running position, the web being severed between the winding rolls while both said rolls are in co-operative relation with the under roll.

3. The combination of delivering-means for a web of paper, winding-means therefor including an under-roll over which the web passes, two winding-rolls, and means arranged to support both said winding-rolls in co-operative relation with said under-roll, respectively, in starting and running position, and transferring one of said rolls from its starting to its running position while it is being rotated.

4. The combination of delivering-means for a web of paper, winding-means therefor including an under-roll over which the web passes, two winding-rolls, and means arranged to support both said winding-rolls in co-operative relation with said under-roll, respectively, in starting and running position, one of said rolls being removable when in its running position, and the other roll being removable from its starting to its running position, while still maintaining its co-operative relation with the under roll, the web being severed between the winding rolls while both said rolls are in co-operative relation with the under roll.

5. The combination of delivering-means for a web of paper, winding-means therefor including an under-roll over which the web passes, two winding-rolls, and means arranged to support one of said winding-rolls in co-operative relation with said under-roll, in running position, and the other winding-roll free from co-operative relation therewith, in waiting position, and subsequently in co-operative relation therewith, in starting position, while the other roll is still supported in co-operative relation therewith in running position, the web being severed between the winding rolls while both said rolls are in co-operative relation with the under roll.

6. The combination with delivering-means for a web of paper, winding-means therefor comprising two winding-rolls, two movable frames, each adapted to support a winding-roll and arranged for the transference of a winding-roll from one to the other frame, and an under-roll over which the web passes, with which the winding-rolls borne by both frames may cooperate at the same time, the web being severed between the winding rolls while both said rolls are in co-operative relation with the under roll.

7. The combination with delivering-means for a web of paper, winding-means therefor comprising an under-roll over which the web passes, two winding-rolls, two movable frames, one for each winding roll, both of said frames adapted to support their winding-rolls in position for co-operation with said under-roll at the same time, said frames being arranged to provide for the automatic transference of the winding-roll from one to the other frame, while maintaining its co-operative relation with the under-roll.

8. The combination of delivering-means for a web of paper, winding-means therefor including an under-roll, two winding-rolls adapted for co-operation with said under roll, to be rotated thereby, means removably supporting said winding rolls in spaced apart relation, one in starting and the other in running position on the under-roll, to admit of the web being severed between them.

9. The combination of delivering-means for a web of paper, winding-means therefor including an under-roll, two winding-rolls adapted for co-operation with said under roll, to be rotated thereby, means removably supporting said winding rolls in spaced apart relation, one in starting and the other in running position on the under-roll, to admit of the web being severed between them, one of said winding rolls being transferable from starting to running position after the winding roll in running position has been removed from its support.

10. The combination of delivering-means for a web of paper, winding-means therefor including an under roll, two winding-rolls, adapted for co-operation with said under roll, to be rotated thereby, means removably supporting said winding-rolls, one in waiting position and subsequently in starting position, and the other in running position both on the under roll, said rolls being arranged in spaced apart relation to admit of the web being severed between them.

11. The combination with delivering-means for a web of paper, winding-means therefor comprising an under-roll, two winding-rolls, two movable frames, one arranged to receive boxes on the journals of a winding-roll, and the other arranged to receive the journals of the roll, the winding-roll when supported by either frame being arranged for co-operation with said under-roll.

12. The combination with delivering-means for a web of paper, winding-means therefor comprising an under-roll, two winding-rolls, a movable frame arranged to support a winding-roll in starting position with respect to said under-roll, and another frame arranged to support a winding-roll in running position with respect to said under-roll, movement of said movable frame transferring a winding roll to the other frame.

13. The combination with delivering-means for a web of paper, winding-means therefor comprising an under-roll, two winding-rolls, a movable frame arranged to support a winding-roll in waiting position and subsequently in starting position with respect to said under-roll, and another frame arranged to support a winding-roll in running position with respect to said under-roll, said movable frame being arranged to transfer a winding roll to the other frame. 65
14. The combination with delivering-means for a web of paper, winding-means therefor comprising an under-roll, two winding-rolls, a frame pivoted eccentrically to the axis of said under-roll, arranged to support a winding-roll in position for coöperation therewith, and another pivoted frame arranged to support a winding-roll in position 70 for coöperation therewith, said eccentrically pivoted frame being arranged to transfer a winding roll to the other frame. 75
15. The combination with delivering-means for a web of paper, winding-means therefor comprising an under-roll, two winding-rolls, a frame arranged to support a winding-roll in running position with respect to the under-roll, means arranged to support a winding roll in starting position 80 with respect to the under-roll which is movable to transfer said roll to the running frame. 85
16. The combination with delivering-means for a web of paper, winding-means therefor comprising an under-roll, two winding-rolls, a frame arranged to support a winding-roll in running position with respect to the under-roll, movable-means arranged to support a winding-roll in waiting 90 position with respect to the under-roll and subsequently in starting position with respect thereto, and subsequently in position to transfer said roll to the running frame. 95
17. The combination with delivering-means for a web of paper, winding-means therefor comprising an under-roll, two winding-rolls, a frame arranged to support a winding-roll in running position with respect to the under-roll, and movable means arranged to support a winding-roll in waiting position with respect to said roll, and subsequently in starting position with respect thereto, and subsequently in position to transfer said winding-roll to the other frame, said winding-roll being moved by the accumulation of paper thereon to the running frame. 100
18. The combination with delivering-means for a web of paper, winding-means therefor comprising an under-roll, two winding-rolls, a frame arranged to support a winding-roll in running position with respect to the under-roll, means to support a winding-roll in starting position with respect to the under-roll and to permit bodily movement of said roll by the accumulation of paper thereon for its automatic transfer- 105
19. The combination with delivering-means for a web of paper, an under-roll over which the paper passes, a winding-roll, movable-means arranged to support said roll in coöoperative relation with the under-roll and permit movement of said roll radially by the accumulation of paper thereon and also permit movement of said roll about the axis of said under-roll to move it from one to another position. 110
20. The combination of delivering-means for a web of paper, winding means therefor comprising an under roll, over which the web passes, two winding rolls, two movable roll-supporting frames, one adapted to support a roll in waiting, and subsequently in starting position, in coöoperative relation with the under roll, to be rotated thereby, and the other adapted to support a roll in running position in coöoperative relation with the under roll, to be rotated thereby, the running frame being movable to admit of the web being wound thereon, and the filled roll to be removed, and the waiting and starting frame being movable to shift an empty roll from a position free from engagement with the under roll into coöper- 115
21. The combination with delivering-means for a web of paper, and winding-means therefor comprising an under roll, two winding rolls, means to support one of said rolls in starting position, and the other roll in running position, both in coöoperative relation with the under roll to be rotated thereby, and spaced apart to provide a length of web extended over the surface of the under-roll, whereby the web may be severed, and its newly-formed end-portion deflected onto the empty winding-roll. 120
22. The combination with delivering-means for a web of paper, winding-means therefor, a chute disposed with respect to the delivering-means, to receive the web while the web is being delivered but is not passing to the winding-means, and means associated with the chute for severing the web passing therewith, and projecting the new free end-portion toward the winding-means. 125
23. The combination with delivering-means for a web of paper, winding-means therefor, guiding-means for the web ar-

ranged between the delivering-means and winding-means, a chute arranged adjacent to the delivering-means, to receive the web 5 while the web is being delivered but is not passing to the winding-means, and means associated with said chute arranged to sever the web and project a new free end-portion thereof forward onto said guiding-means.

10 24. The combination with delivering means for a web of paper, winding-means therefor, guiding-means for the web arranged between the delivering-means and winding-means, a chute arranged adjacent 15 to the delivering-means, to receive the web while the web is being delivered but is not passing to the winding-means, and means associated with said chute arranged to sever 20 the web and project a new free end-portion

thereof forward onto and along the guiding-means and into engagement with the winding-means.

25. The method herein described of winding paper continuously which consists in severing the web of paper on a moving surface in a slanting direction, and bringing into coöperative relation with said moving surface an empty winding-roll upon which the newly-formed end-portion is wound while the other end-portion produced by severing the web is being wound on another winding-roll. 30

In testimony whereof, I have signed my name to this specification, in the presence of 35 two subscribing witnesses.

CHARLES ELMER POPE.
